SAFETY DEVICE FOR PRESSES.

John Hoza, Belcamp, Md.

Application May 18, 1940, Serial No. 336,043

7 Claims. (Cl. 192—133)

The present invention relates to safety devices for presses such as are used for pressing soles and insoles in the manufacture of footwear. The invention has in view the prevention of injury to the operator during pressing of the work piece if, during positioning of the sole or insole, he should leave one hand between the patterns or pressing elements, whilst with the other hand he removes the pressed sole or insole from between the patterns.

Accordingly, an object of the invention is a safety device the operation of which is effected through the engagement of a control element, for example a curved protecting stirrup, by the operator's hand during the pressing of the work piece, whereby the press is brought to a standstill and the desired protecting distance remains between the patterns.

Another object of the invention is a safety device comprising a spring-pressed abutment member movable to a position between parts moving with the patterns to co-operate therewith and limit the approach of said patterns one to another, said abutment member normally being retained inoperative by a detent, the release of which is effected by said control element when the operator's hand is in a position of danger.

A further object is a safety device as just defined in which the throwing over of the abutment also effects simultaneously the stoppage of the machine, for example by reason of a part moving with said abutment co-operating with a door contact controlling the electrical circuit of the drive.

Still another object is a safety device as above defined having means for re-setting the abutment member after the latter has been thrown into the operative (stopping) position.

For the better understanding of the invention reference will now be made to the accompanying drawings, which illustrates by way of example one construction according to the invention.

In the drawings:

Figure 1 is a side view of the protecting device mounted on a sole and insole press;

Figure 2 is a plan view in partial section on line A—A of Figure 1;

Figure 3 is a side view showing the protecting device in the freed or operative position.

Referring to the drawings, a safety device according to the invention is illustrated as applied to a press comprising a guiding rod 1 on which during operation of the machine a lower slide 18 moves to and fro with a lower pattern B. An upper pattern C is fixed in the upper part of the press and faces towards the lower pattern B. The safety device, which is firmly mounted with the aid of a frame 9 on the guiding rod 1, comprises a curved bow-shaped protecting stirrup 2 of which one end is extended and is inserted in

a bent arm 3 pivoted on a bracket 4 by means of a screw 7. The extended arm of the curved stirrup 2 has a longitudinal slot 5 through which passes a screw 6 serving for holding fast the stirrup. The said screw and slot connection enables the stirrup 2 to be pulled forward or pushed in and thereby adapted to the form of the patterns in use. The curved stirrup 2 and arm 3 secured fast to one another in this manner thus form a lever rotatable about the screw 7. In the end of the arm 3 a pin 8 is inserted which passes through an opening in a housing on the frame 9 of the safety device and co-operates with a recess 10 in a block or "wedge" 11 which is adapted to be slid forward between relatively movable parts of the press to prevent complete approach of the patterns, said pin 8 serving to lock the wedge in the retracted position. For the initial setting of the safety device a rod 13 is provided having a Bakelite knob 12. In order to set the press in operation the rod 13 is pressed into the machine, whereby the other end of this rod presses the wedge 11 towards the right, that is into the housing on the frame 9. The wedge moves against the action of a spring 14, which latter is thereby compressed. Meanwhile the pin 8 enters the recess 10 of the wedge and the latter is thus secured.

The spring is compressed on a rod 15 which is screwed fast in the wedge 11 so that it takes part in the to and fro movement of the wedge. The other end of the rod 15 passes freely through an opening in the housing on the frame 9 and bears on the sprung plate 16 which forms one part of a door contact which is mounted on a bent bracket 17 fast on the frame of the safety device.

The safety device having been rendered ready for operation by pressing the knob 12, the machine can be set in operation. The patterns can complete the pressing operation, this position of the patterns being illustrated in Figure 1. If now the operator places a work piece between the patterns with his left hand and with his right hand removes another work piece from between the patterns, but does not withdraw his hand in time from the machine, then the lower upwardly moving pattern lifts his hand, whereby the latter comes against the curved stirrup 2 which is raised and sets the safety device in operation as follows:

The lever formed by the stirrup 2 and slotted arm 3 swings about the screw 7 whereby the pin 8 is disengaged from the recess 10 of the wedge 11. The latter is thereby released so that the strongly compressed spring 14 slides it quickly towards the left together with the rods 13 and 15. Thereby the projecting end of the wedge comes between the frame 9 of the safety device and the upwardly moving lower slide 18 as shown

in Figure 3 so that the patterns cannot fully close; that is, a sufficient distance for protection remains between them (Figure 3) so that the hand of the worker is not injured. Simultaneously moreover, due to the sliding out of the wedge 11, the press is immediately stopped because the wedge takes along with it the rod 15 bearing on the sprung plate 16, whereby the door contact operates so that the electrical circuit of the drive is broken and the machine 10 stopped. The safety device can be reset to the normal position by pushing the Bakelite knob 12 towards the machine. The wedge 11 is again pressed into the housing on the frame, the spring 14 compressed, and the pin 8 brought into the slot 10 of the wedge, whereby the latter is locked against flying out. Simultaneously the rod 15 again engages the sprung plate 16, the door contact is made ready for operation and the machine can again be started.

I claim:

1. In a press, such as for soles and insoles, having a pressing element slidable on a guide towards another pressing element, a frame mounted on the guide, a safety device comprising an abutment member slidably mounted with respect to the frame and slidable into a position between the frame and a part moving with the sliding pressing element to co-operate therewith and limit the approach of said sliding element to the other element, said abutment member normally being retained out of said position, and a control member so disposed in relation to the pressing elements that the operator's hand, if between said elements during their relative approach, is carried into engagement with the control member to operate the latter for moving the abutment member into said position.

2. In a press for soles and insoles, a stationary pressing element and a slidable pressing element movable toward and from the stationary element, a guide for the slidable element, a frame mounted on the guide, a safety device comprising an abutment member slidably mounted with respect to the frame and slidable into a position between the frame and a part moving with the slidable pressing element to co-operate therewith and limit the approach of said slidable element to the other element, said abutment member normally being retained out of said position, and a control member in the form of an adjustably mounted bowed stirrup embracing the entry end of the pressing elements and so disposed in relation to the pressing elements that the operator's hand, if between said elements during their approach, is carried into engagement with the control member to operate the latter for moving the abutment member into said position.

3. In a press for soles and insoles, a stationary pressing element and a slidable pressing element movable toward and from the stationary element, a guide for the slidable element, a frame mounted on the guide, a housing mounted on the frame, a safety device comprising a spring urged abutment member slidably mounted in the housing and movable by its spring to a position between the frame and a part moving with the slidable pressing element to co-operate therewith and limit the approach of said slidable element to the other element, a detent normally holding said abutment member out of said position, and a control member connected with said detent and so disposed in relation to the pressing elements that the operator's hand, if between said elements

during their approach, is carried into engagement with the control member to operate the latter for releasing the abutment member.

4. In an electrically operated press for soles and insoles, a stationary pressing element and a slidable pressing element movable toward and from the stationary element, a guide for the slidable element, a frame mounted on the guide, a safety device comprising an abutment member slidably mounted with respect to the frame and slidable into a position between the frame and a part moving with the slidable pressing element to co-operate therewith and limit the approach of said slidable element to the other element, said abutment member normally being retracted out of said position, a switch adjacent the retracted abutment member for controlling the drive of the press, a control member engageable by the hand of an operator and operable to bring said abutment member into said position for limiting the relative approach of the pressing elements, and means moving with said abutment member to actuate the switch upon initial movement of the abutment member to stop the drive of the press.

5. In a press for soles and insoles, a stationary pressing element and a slidable pressing element movable toward and from the stationary element, a guide for the slidable element, a frame mounted on the guide, a safety device comprising an abutment member slidably mounted with respect to the frame and slidable into a position between the frame and a part moving with the slidable pressing element to co-operate therewith and limit the approach of said slidable element to the other element, said abutment member normally being retained out of said position, a control member so disposed in relation to the pressing elements that the operator's hand, if between said elements during their approach, is carried into engagement with the control member to operate the latter for moving the abutment member into said position, and a hand operated rod secured to the abutment member for re-setting said abutment member in its inoperative position.

6. In a press for soles and insoles, a safety device including a slidable abutment member slidable into a position between relatively movable parts of the press to rigidly block the movement of a pressing element at a fixed point in the pressing stroke thereof in order to prevent completion of said pressing stroke and cause a gap to be left between the pressing elements independently of continuance of the drive therefor, and control means adapted to be operated by the operator's hand if the latter is between the pressing elements, and in that case to slide the abutment member into the blocking position before the moving pressing element reaches the said fixed point in its pressing stroke, so that the pressing element will be blocked upon reaching that point.

7. In a press for soles and insoles, a safety device as claimed in claim 6, and further comprising control means for cutting off the drive of the moving pressing element, said further control means being operated automatically immediately upon movement of the abutment member to the blocking position, the arrangement thus being such that first the drive of the pressing element is cut off and at a later point in its stroke the pressing element is rigidly blocked by the abutment member.

JOHN HOZA.
